United States Patent Office.

JOHN MCLEOD MURPHY, OF NEW YORK, N. Y., ASSIGNOR TO JAMES LORIMER GRAHAM, OF SAME PLACE.

Letters Patent No. 97,954, dated December 14, 1869.

IMPROVEMENT IN PACKING-CASES FOR OIL-CANS.

The Schedule referred to in these Letters Patent and making part of the same.

To all whom it may concern:

Be it known that I, JOHN MCLEOD MURPHY, of the city, county, and State of New York, have invented a new and improved Packing-Case for Oil-Cans, intended to apply to a can provided with my improved nozzle, for which a patent was granted October 19, 1869, No. 95,927; and I do hereby declare that the following is a full, clear, and exact description thereof, which will enable those skilled in the art to make and use the same, reference being had to the accompanying drawings, forming part of this specification.

This invention relates to improvements in transportation-cases for oil and other cans, to be used for the protection of the said cans, which are shipped full, and returned empty for refilling, and are consequently exposed to injury by rough handling, and otherwise.

The invention consists of an arrangement especially adapted for use with cans provided with an improved cut-off nozzle, which is the subject of an application for a patent made by me, and bearing even date herewith, which said improvement comprises the application to the ordinary vertical nozzles, of a lateral spout, connected to the side, and arranged to open an escape-passage for the contents when the said spout is turned into the right position, which position is that best adapted for pouring from the can into another vessel, and in which the said spout projects through a slot in the side of the packing-case enclosing it, the said case being provided with an opening, and a door for closing the same, adapted for it.

Figure 1 represents a side elevation of my improved can, and

Figure 2 represents a plan view, with a part of the top broken off.

A represents the tin packing-case, containing the oil or other substance, and provided with the turning cut-off spout G, attached to the vertical nozzle C, closed by a screw-cap, D, which, as these cans are at present constructed, must be removed for pouring out the contents of the cans, and requires that the top, or

a portion of the top of the exterior packing-case be removed, whereas my improved nozzle requires only the opening of a small space in the side below the cover, and the spout projects so far beyond the side of the case as to afford the best possible conditions for pouring from the nozzle C.

E represents the exterior packing-case, which is made of wood, fitted to the can snugly, and having the top screwed down tightly.

F represents a small door, fitted into a space cut out of one side at the upper edge, and extending from the corner, about half the length of the side where it is hinged at G.

When closed, it may be fastened at the corner by a screw, H, in the ordinary way of fastening the other parts of the case, or by any other fastening.

It is arranged relatively to the spout G, so that the latter, when turned to open the passage for the contents, will project through the space, (the door being open,) as represented in the dotted lines at I, for pouring.

After pouring, the spout is turned back and the door closed under the edge of the cover.

This arrangement provides a very cheaply-constructed and durable case, which, combined with the cans for which it is intended, constitutes a very useful package for fluids.

Having thus described my invention,

What I claim as new, and desire to secure by Letters Patent, is—

The combination, with a tin or other sheet-metal packing-can, provided with a turning cut-off nozzle, C G, of an exterior packing-case, provided with a door, F, arranged relatively to the said nozzle, substantially as specified.

The above specification of my invention signed by me, this 5th day of August, 1869.

JNO. MCLEOD MURPHY.
